UNITED STATES PATENT OFFICE

GEORGE C. BEIDLER, OF ROCHESTER, NEW YORK

APPARATUS FOR TREATING PHOTOGRAPHIC FILMS

Application filed August 5, 1927. Serial No. 210,894.

This invention relates to a method of and means for treating photographically sensitized elements whereby photographically exposed sensitized elements are subjected to 5 successive treatments which result in developing the said elements, fixing and washing the same, and by which the elements are dried and delivered by the apparatus in a finished state.

10 The invention may be associated with cameras which expose the sensitized element to light and with devices preferably within and forming a part of the apparatus for developing the said sensitized element and, as illustrating the best example, so far as known, for carrying the invention into successful practice, it is disclosed as associated with a camera or exposing apparatus and a developing instrumentality associated therewith.

15 The term "sensitized element" has been employed herein, but in the interests of brevity, such element will be hereinafter referred to as a "film".

In the commercial cameras which are employed for reproducing photocopies of commercial documents, sensitized paper is drawn from a roll through an exposing chamber and, thereafter, appropriate lengths of the paper are cut and treated as the exposures 20 are made. Such sensitized paper is the object to which reference has been made as a sensitized element; although, obviously, other flexible material capable of carrying an emulsion might be employed as a substitute for the paper, and it is the purpose of the inventor that any such material so coated will be comprehended within the term "film".

It is an object of the invention to provide novel means which will withdraw film from 25 the aforesaid developing instrumentality and deliver it to a fixing bath. The fixing bath, in the present embodiment of the invention, is located in such proximity to the developing instrumentality that film being moved from a developing receptacle will be subjected to an initial coating of fixing fluid while it is being delivered to the fixing bath. It is well known that the time required for 30 development of a film is usually quite less than the time required for the fixing agent

to act, and, hence, provision is made for storing a given number of films in the fixing bath; therefore, in the present showing, provision is made for treating approximately ten films in the fixing bath prior to the time that the first of the group delivered thereto is removed and, thereafter, each time a film is delivered to the fixing bath, one is removed therefrom.

It is the purpose of this invention to provide novel means whereby, during each successive operation of the means for drawing the exposed film and delivering it to the developing fluid, the instrumentalities by which the film is moved from the fixing bath will be actuated and that during such actuation, films in the fixing bath will be successively shifted with respect to the fixing bath or the container for the fixing bath.

It is a further object of the invention to 35 provide novel means operatively associated with the said means for removing film from the fixing bath, for receiving the fixed film and delivering it to a washing bath or tank in a flat state on water or fluid in the washing tank; and it is furthermore an object to provide novel means whereby the film is moved longitudinally of the washing tank clear of the sides of said tank and in a manner to prevent adherence of the film with the sides 40 of the tank or other interruption to the said movement of the film in the washing tank.

It is furthermore an object to provide novel means by which the film is subjected to efficient action of the water or washing fluid; and furthermore, to provide novel means by which the films delivered to the washing fluid are successively shifted therein intermittently with or during the delivery of the films to the washing tank; and the invention 45 further contemplates the provision of novel means for successively removing the films from the washing tank.

In the present embodiment of the invention, the washing tank is intended to hold approximately twenty films, and after said films have been delivered to it, one film is removed each time one is delivered. It will be understood that the device can be proportioned so that the washing tank may contain more or less 50

films, but that would depend upon the time desirable for completing the washing process. As found in practice, during the time that approximately twenty films have been delivered to the washing tank, the washing process for the first delivered film has been satisfactorily completed, but, if under other conditions, it would be desirable to have the film remain a greater or less time in the washing fluid, the shifting device or conveyer of the washing tank could be changed proportionally to the shifting device or conveyer of the fixing tank so as to bring about proper relative movements of the mechanism.

Furthermore, in carrying the invention into practice, it is an object to provide novel means for transferring film from the washing fluid or tank and delivering it to a drier which is operative to dry the film and deliver it in a finished state.

It is a still further object of this invention to provide novel means whereby the aforesaid instrumentalities for transferring film from the developing fluid and delivering it to the fixing fluid, the mechanisms for moving the film in the fixing fluid and removing it therefrom, as well as the mechanism for moving film into the washing tank, the mechanism for removing film from the washing tank, the mechanism for delivering film to the drier, and the mechanism for operating the drier, are actuated in coordination intermittently or in time, according to the functions ascribed to the several parts; and furthermore, to provide a novel control whereby the actuation of one element, such as the film cutter, may control the aforesaid actuating mechanisms.

With the foregoing and other objects in view, the invention consists in the details of construction, and in the arrangement and combination of parts to be hereinafter more fully set forth and claimed.

In describing the invention in detail, reference will be had to the accompanying drawings forming part of this application, wherein like characters denote corresponding parts in the several views, and in which—

Figure 21 illustrates a detail view in plan of a part of the gearing; and Figure 22 illustrates a sectional view through the worm drive.

In carrying the invention into practice and as illustrated in the present embodiment of the invention, the casing A is intended for containing the film and is supplied with mechanism under the teachings of the patents numbered 1,346,780 and 1,359,481 to George C. Beidler, for transferring the film, exposing it and delivering it to a developing tank and instrumentalities associated with it, generally identified by the letter B. In proximity to the developing tank, a film transfer C is designed to receive film from the developing tank and to convey it or transfer it to a receptacle D which is to contain fixing fluid.

At or near one end of the fixing receptacle there is located a film transfer or conveyer, generally identified by the letter E, whose construction, function and operation will be described in detail hereafter. The film transfer E is operative to remove film from the fixing receptacle and deliver it to a coacting film transfer, generally identified by the letter F, at or near one end of a tank or receptacle G in which the film is washed. As film enters the washing tank, it is moved toward and directed to a film transfer or conveyer H at or near the end of the tank opposite that which contains the transfer F. The transfer H contains mechanism which acts to move film in the tank and thereafter remove it from the tank, and this transfer is

preferably in operative relation to a film drier, generally identified by the letter I, which, as will presently appear, is provided with mechanisms that dry the film and deliver it in a finished state.

5 In order that the several instrumentalities referred to, generally identified by the letters A to I, may be comprehended, each will be described in detail in order.

10 As those skilled in the art understand the structure and operation of the so-called commercial cameras and the manner in which film is taken from a roll or core and delivered to an exposing chamber and thereafter transferred to a receptacle at the bottom of the exposing chamber, reference to the elements of such a camera is believed to be unnecessary.

15 The receptacle 25, in the present showing, is intended to receive the exposed film for development and the developer receptacle has a coil-form film holder 26 in which the film is temporarily stored while it is being developed. Mechanisms are associated with the developing receptacle which are operative to 20 remove film from the developing receptacle and deliver it to the film transfer C. The application of this inventor, Serial Number 25 64,560, affords a disclosure of the mechanisms for transferring film associated with the developing receptacle and said application has 30 matured into Patent No. 1,664,729, dated April 3, 1928.

The film transfer C is intended to subject 35 the film in its travel to an initial coating of fixing fluid before it is finally delivered to the fixing bath, and it has been found in practice that this so-called momentary initial application of fixing fluid to the developed film serves to arrest development and to render it 40 possible to temporarily store the film in the fixing receptacle while the film is being further and completely fixed without any appreciable change of the photograph on the film.

The film transfer just mentioned is located, 45 in the present embodiment of the invention, at the front end of the fixing fluid receptacle or tank, and films are deposited into the fixing fluid receptacle one at a time and in superimposed relation to one another, as has been 50 stated.

Means in, or associated with, the fixing fluid tank are operative to move the film step by step downwardly in the fixing fluid and after a predetermined number of films are in the 55 fixing fluid, one film is removed from the fixing tank each time one is deposited therein. The film submerging and transferring means just mentioned constitutes that part of the apparatus generally identified by the numer- 60 al E and it is shown in section, Fig. 4.

This submerger and conveyer or transfer is shown as including end frames or plates, such as 26', and a cross bar 27 having journal bearings 28 in which shafts 29 are rotatable.

65 A gear wheel 30 on the upper end of each

shaft meshes with a gear wheel 31 of a transversely journaled shaft 32 intermittently driven, as will presently appear. The gear wheel 30, or a part associated with it, is provided with a lug or pin 33 which, during 70 the rotation of the shaft 29, rides on the upper surface 34 of the journal bearing, but the said journal bearing has a notch or recess 35 on one side which permits the shaft 29 to move slightly axially when the pin or lug 33 registers with the recess. Upon rotation of the shaft 29, however, the lug or pin rides out of the slot or recess and then travels on the upper surface 34 of the journal bearing until the shaft has made a complete rotation, when it again moves downwardly with the pin 33 entering the seat 35. The gear wheels 30 and 31 mesh rather loosely when the parts are in the position shown in Fig. 4, but a clearance is provided which will permit the gear wheel 30 to rise with relation to the gear wheel 31 without impairing the teeth of the wheels when they are driven.

The worm 36 is arranged on the shaft 29 and, in the present embodiment of the invention, this worm comprises a plurality of convolutions intended to receive film 37 and carry it downwardly in the fixing fluid. The upper blade or volution of the worm is flared slightly with respect to the next succeeding volution or blade to provide a mouth or clearance into which the film will ride or be guided to insure coactive relation of the film and the worm during the steps of the operation. The lowermost blade or volution 38 of the worm is shaped to form an elongated recess or depression 39 in its under surface, and this part of the worm coacts with a drawing or feed roller 40 which is mounted on a shaft 41 journaled transversely of the frame. 100 It is to be understood that in the machine adapted to operate on relatively large sheets, such as that having a width of 24 inches, preferably two submerging worms and instrumentalities for operating them will be 110 provided in each submerger and transfer, and, of course, the parts would be duplicated for each of the worms.

A gear wheel 42 is secured on the shaft 41 near one end and it is driven through a train 115 of gearing, generally identified by the numeral 43, from a gear wheel 44 on a shaft 45. The shaft 45 carries a plurality of bushings or rollers 46 and these coat with wheels or rollers 47 on the shaft 48 for drawing film 120 from the fixing fluid, it being shown that inclined ribs or guides 49 extend diagonally upwardly and rearwardly toward the end of the frame and, in operation, films that have been forced upwardly on the inclined supports 49 are guided between rollers 50 and 51 appropriately journaled transversely of the frame and these rollers are driven, as will presently appear, and are operative to carry the film outwardly from whence the films are 130

delivered to means for inserting the films in the washing apparatus, to which reference has been made.

It has been stated that the roller 40 coacts with the bottom plate or volution of the screw conveyer or submerger and this action is intermittent. Each time the conveyer is driven, it is lifted during its initial movement and it makes nearly one complete turn in its elevated position, during which time the film that is lowermost or just near the lower end of the conveyer is released and the film is then between the end of the conveyer and the roller. When the conveyer descends again, as it does when the pin or lug drops into the recess 35, the film is pressed into engagement with the roller or wheel, and the film is thereby forced from the receptacle. It is seen that the recess or depression 39, in the present embodiment of the invention, is curved, and it is the intention of the inventor that it should be elongated concentric with the circumference of the plate of the spiral conveyer in order that clearance will be afforded for the initial movement of the worm as it turns slightly and rises to its elevated position. The relation of parts is such that the bottom of the recess 39 does not come in engagement with the periphery of the roller 40 when the worm is in its lowermost position. The roller 40 should turn freely, but the clearance is such that film will be gripped by the roller 40 when it is interposed between the worm and the roller.

The rollers 50 and 51 are geared together as at 52 and these rollers serve to carry film and, at the same time, squeeze or wring fluid from it in order that only a limited amount of fixing fluid will be carried by the film in its exit from the fixing receptacle. The roller 50 has a trunnion or shaft 53 and a wheel 54, such as a pulley, by which power is transmitted through the use of a gear wheel 55, an idle gear 56, a gear wheel 57 and a gear wheel 58 to drive parts of the mechanism. The wheel 56 is supported by a stub shaft 59 and the wheel 57 is on a shaft 60 that is rotatable in a bearing 61. The inner end of the shaft 60 carries a gear wheel 62 meshing with a gear wheel 63 on the shaft 48 so that by this means, the shaft 48 is positively driven and the elements 47 are turned to move film in conjunction with the rollers 46 in the manner described. The gearing from the shaft 45 to the gear wheel on the shaft 41 is likewise driven to operate the roller 40 which imparts an initial movement to the film resulting in delivering film between the rotating elements 46 and 47.

In order that the film submerger may be operated intermittently, a clutch or pawl and ratchet is interposed between the positively driven wheel 58 and the shaft 32 and, in the present embodiment of this clutch, the wheel 58 has a sleeve or extension 64 provided with

shoulders 65, and a disk 66 secured on the shaft 32 has a pivot 67 on which a dog 68 is oscillatable. The dog has a nose or shoulder-engaging part 69 and hence, when the dog is in engagement with the shoulders or teeth 65, the wheel 58 will drive the shaft 32, whereas, when the dog is out of engagement with the shoulders or teeth 65, the wheel 58 will idle. A spring 70 is anchored to a stationary part of the device and bears against the dog to normally force it into coactive relation with the teeth 65, although means are provided for intermittently holding the dog inactive.

In the present showing, a thrust rod 71 is movable in bearings 72 and 73 supported on the frame and, as shown in Fig. 6, the rod is in engagement with the tail-piece 74 of the dog and thereby the dog is held from engaging the ratchet teeth 65. Means are provided for shifting the rod 71 axially while it is being partially rotated and, to that end, the bearing 73 is provided with a diagonally disposed slot 75 in which a pin 76 that extends radially from the rod 71 will travel so that as the rod 71 turns, the walls of the slot 75 will act as cams against which the pin 76 will operate to move the rod 71 into and out of the path of travel of the tail of the dog. The rod 71 has an arm 77 to which a link 78 is connected for partially rotating the rod during the operation of other parts of the apparatus, as will presently appear.

As it is desirable to move the submerger each time a film is delivered to the receptacle, the power applying mechanism for the submerger will operate when the rod 71 has been moved out of engagement with the dog, since, when this occurs, the spring will press the dog into engagement with the ratchet teeth and thus the movement of the wheel 58 will be communicated to the shaft 32. Immediately upon the release of the dog, it will be carried by the action of the wheel 58 past the rod 71 and, thereafter, the rod will be returned to the position in which it is shown in Fig. 6, when it will again be in the path of travel of the tail of the dog and it will arrest the dog and cause it to disengage the ratchet teeth. Hence, each time the rod 71 is moved out of engagement with the dog, the submerger will be moved to submerge the uppermost film and to carry the successively submerged films downwardly in the fluid until they successively come in the zone of action of the rollers 40.

Preferably, the device is provided with a film guide which is effective to insure the entrance of the film to the submerging device and, in this embodiment of the invention, guiding plates, such as 79, with upwardly flared outer ends 80 are supported at or about the level of the fluid to which film is delivered in the receptacle. The plates 79 are shown as having arms, such as 81, which extend upwardly and these arms are shaped to

embrace a cross bar in which the shafts 29 are journaled, and the said arms may be secured in place by set or clamping screws 82. The films traveling on or near the surface 5 of the fluid which encounters the plates 79 will find their way under the plates to the flared portion of the submerger and this insures the assumption of proper position of the films with relation to the submerging instrumentality.

After film has been submerged step by step in the receptacle just described and has been removed therefrom past the rollers 50 and 51, the film is delivered to a washing tank 15 and, as an aid to the delivery of the film in a flat or relatively flat state to the washing tank, the film is engaged by the coacting film transfer F which includes a frame having side plates 83 in which a shaft 84 is journaled. 20 The shaft may have pulleys or a jacket 85 thereon, over which conveyor bands or belts 86 may travel and the film issuing from the rollers 50 and 51 drops onto the surfaces of the conveyor elements 86. A shaft or roller 25 87 is journaled in the frame and the conveyor elements operate around it and around a drum or roller 88 on a plane below the elements 85 and 87 and in a location between them. Relatively heavy wheels or rollers 89 30 engage the upper surfaces of the conveyer elements 86 and they coact with said conveyer elements so that film received on the apron or conveyer element 86 is positively carried by the conveyer element, owing to the friction or pressure of the rollers 89 which holds 35 the film in engagement with the conveyer element and augments the feeding or moving action of this transfer. It is shown in the drawing that the periphery of the roller 87 40 is preferably above the level 90 of the water in the washing tank 91 so that as film passes the roller 87, it is delivered on the surface of the water in the washing tank and is pushed longitudinally of the washing tank 45 practically on the surface of the water. The shaft 89' of the rollers 89 is preferably movable vertically in a slot 89² and this allows an adjustment of the position of the rollers 89 to compensate for variance in the tension 50 of the conveyer elements 86.

The coacting film transfer F is located at or near the receiving end of the film washing tank 91 and the film is thoroughly washed in said tank, by reason of the fact that constantly flowing water is circulated in the tank. Fresh water is delivered to the tank 55 and after it has passed over and about the film, it escapes through a waste pipe. It is the purpose of the inventor to utilize the force of the inflowing water to facilitate the delivery of film and the movement of the film in the tank in order that the film will be impelled and directed longitudinally of the tank into the zone of a film submerger and transfer, while at the same time the film is

being washed and, to the end just stated, the present embodiment of the invention includes the following instrumentalities, viz: the side walls of the tank are each provided with a plurality of approximately vertically extending slots 92, which form jets for the flow of water, whose walls are diagonally forward with respect to the direction of movement of the film in the tank, and the slotted portion of each wall has an external header or pipe 70 75 93 through which water is delivered to the slots or ports 92. By this arrangement, water that is being delivered to the tank through the ports under pressure serves to maintain the edges of the film clear of the side surfaces of the tank and prevents a drag of the film such as might result if the edges of the film engaged the sides of the tank. The force of the water discharging from the jets 92 also exerts a force on the film that aids in carrying it longitudinally of the tank so that these relatively deep jets augment the film washing action, and the water issuing therefrom aids in moving the film longitudinally of the tank and prevents the edges of 90 the film from encountering the sides of the tank to a degree which might impair the free movement of the film. Water is supplied to the pipe or header 93 through any suitable conduit or pipe, such as 94, which may be connected to a water source, such as a header 95.

Further means are provided for the delivery of water to the tank and, while different piping systems may be employed, the said header 95, here shown, extends transversely 100 of the tank near one end and water may be delivered to it in any suitable manner, as through a connection 96. Pipes 97, to any number found desirable or necessary, connect with the header and they extend longitudinally of the tank and terminate in jets 98 through which water is emitted upwardly and longitudinally of the tank, and the action of the water aids in buoying the film and moving it rearwardly of the tank, since the current or flow of water in the tank is toward the end opposite that in which the header is located. Other jets 99 are located in upwardly inclined positions under the auxiliary film transfer in the receiving end 110 of the tank, and the force of water therefrom aids in washing the film and moving it longitudinally of the washing tank.

As a further means for delivering water to the tank where said water will impinge 120 the film and aid in dislodging the fixing fluid and chemicals, which it is desirable to remove during the washing process, water pipes 100 are supported above the tank and they extend transversely thereof. The pipes 100 125 have downwardly and rearwardly projecting jets 101 which discharge water under appropriate pressure to the upper surface of the film as it is delivered to the tank, and the force of the water from these jets also aids 130

the movement of the film longitudinally of the tank. The pipes 100 may be connected to any suitable source of water supply, but they are here shown as associated with a header 102. Valves or cocks 103 may be supplied for controlling the flow of water. Therefore, under the influence of the action of the film transfer and the water flow and forces, film that has been successively delivered to the washing tank is moved toward the end remote from the receiving end and into cooperative relation with a submerger and film transfer H.

The film submerger and transfer H, in so far as the submerging instrumentalities and drives are concerned, is of the same construction as the submerger and transfer E, except that the submerging screw conveyer has a capacity for operating in conjunction with approximately twenty films instead of approximately ten and, as understood, this means but the provision of additional volutions or blades of the conveyer to provide spaces for the film equal to the number of films which it is desirable to have in the tank prior to the removal of the lowermost film. With this understanding, therefore, attention is directed to the description of the mechanism shown in Figs. 4 and 5, particularly, so that one skilled in the art will understand the structure of the film submerger and transfer H.

The film submerger and transfer H, however, has added features, as compared with the submerger and transfer E, but these added features have to do with delivery of film to a drier, which has been generally identified by the letter I. Rollers 104 and 105 of the submerger and transfer H, which correspond with the rollers 50 and 51 of the submerger and transfer E, are associated with a metal roller 106 under which the film 107 travels from the washing tank. The roller 106 has the function of pressing the film and removing any coating of water that may be on the surface after it passes between the rollers 104 and 105. The roller 106 is journaled in link bearings 108, the lower ends of which are loosely applied to trunnions of the roller 104.

The rollers 104 and 105 are geared together, as at 109, and the film is taken from the film transfer H by them and delivered to a conveyer 110. The film in its travel follows the direction of the arrow 111, (Figs. 1 and 3). The conveyer just mentioned consists of a frame rigid with the frame structure of the film transfer H and it has depending arms 112 with a shaft 113 journaled in the upper ends of the arms, and a shaft 114 journaled in the lower ends of the arms. The shaft 113 is positively driven through a train of gearing 115. The shafts 113 and 114 have pulleys, such as 116, over which conveyer bands 117 are operated, and these conveyer bands re-

ceive the film and support it while it is being delivered between the drum 118 and the apron 119 of the drier. The drum 118 is, of course, provided with heat, but as drying drums of this type are known, and as the means for supplying heat thereto is also well known, the internal construction of the heating means for the drier will not be described in detail. It is obvious from an inspection of Fig. 1 that the apron 119 is looped around a roller or pulley 120 and around a roller or pulley 121 in spaced relation to the roller or pulley 120 so that the apron is continuous in form, operating around the two rollers 120 and 121, around the drum 118 and in engagement with idlers 122, 123, 124 and 125, arranged in suitable bearings or brackets on the frame of the machine. Film, which has been carried around the drum past the roller 121, is forced into engagement with a curved deflector 126 which causes it to bend or double on itself and traverse a course indicated by the arrows 127, (Fig. 3), to a receiver or pan 128 where the film is received in a finished dry state.

The treatment of film from the time it is exposed to the time that it is delivered in said finished state and the mechanisms heretofore described are positively driven intermittently, synchronously, or in time, so that successively or simultaneously, film is undergoing treatments leading to the production of finished photocopies, photoprints or photographs.

Preferably, that part of the mechanism which is intended to develop the film and fix it is installed in a photocopying machine associated with the exposing chamber and casing, and subject to the movement of the instrumentalities which have to do with the focusing, and in this disclosure of the invention, it is so shown, although, obviously, these may be changed, under certain conditions. The developing tank and the fixing fluid tank are so associated with the camera structure, or the exposing means, as to move therewith and, since, in focusing, the relation of these parts with respect to the frame structure 129 is changed, it is also desirable to, at the same time, shift the position of the washing tank and drier in order that they may be properly located to receive film from the fixing bath. To the end just mentioned, a frame 130, on which the washing tank and drier are installed, is provided with wheels 131 which travel on a track 132. A link or connection 133 couples the frame 130 to a stud 134 which depends from the camera structure and, therefore, when the camera structure is moved in focusing, the frame 130 moves to exactly the same extent as the camera structure is moved so that the operating relation of the different parts is maintained.

The arms 77 have been described as operating the thrust rods 71, one of which is asso-

ciated with the unit E and the other is associated with the unit H. The link 78 connects the arms so that they move together when the lever 135, which operates the cutting mechanism of a machine of this character, is manipulated. The cutting lever swings in the direction of the arrow 136 and the lower end of the lever moves into engagement with a lever 137 oscillatable on a pivot 138, and the end of one of the links 78 is connected to the end of the lever 137 so that as the lever is oscillated, the links are moved longitudinally. A spring 139, engaging the lever 137, serves to return it to its normal position immediately upon the release of the lever 135. When the links 78 are thus moved initially in the direction of the arrows 140, the thrust rods 71 will be partially turned and the pins on the thrust rods will cam in the slots of the bearings in which they are journaled and by this means the thrust rods are moved out of engagement with the dogs manually and returned through the action of the said spring, although, of course, any appropriate means may be provided for intermittently arresting and releasing the dogs.

The apparatus in its assembled state is, in the present embodiment of the invention, provided with a motor drive and, to that end, an electric motor 141 is mounted on the frame and a driven pulley 142 operates a flexible element 143, such as a belt, chain, or the like, over a wheel 144 on a shaft 145. A worm 146 on the said shaft drives a worm wheel 147 on a shaft 148. A gear wheel 149 on the shaft 148 meshes with a gear wheel 150 on one end of a shaft of the roller or drum 120 of the drier. A shaft 151 is journaled in appropriate bearings on the frame and a gear wheel 152 thereon meshes with the gear wheel 150 and with a gear wheel 153 on the trunnion of the drier conveyer roller 120. A sprocket chain 154 on the shaft 151 operates over a sprocket wheel 155 for driving the mechanism of the unit H.

A shaft 156 is journaled transversely of the frame at the end opposite the motor and this shaft carries a sprocket wheel 157 and a pulley 158. A sprocket chain 159, engaging a sprocket wheel 160, drives the shaft 156 through the engagement of the chain 159 with the wheel 157. Any appropriate guide or adjusting means, such as 161, may be employed in the machine.

The end of the shaft 156 opposite that shown in Fig. 7 has a sprocket wheel 162 engaging a sprocket chain 163, operating over a sprocket wheel 164 on the shaft 84 of the unit F so that by this means, this auxiliary conveyer is driven.

The pulley 158 is belted to the pulley 54 and thus the unit E is driven.

I claim:

65 1. In an apparatus for treating films, an

exposing chamber for the films, a receptacle to which films are delivered for development, a receptacle in proximity thereto for receiving films for fixing the same, means for moving the films downwardly in the said receptacle, means for removing the lowermost of the films successively, a washing tank, means for conveying the said films to the washing tank and delivering them in approximately horizontally superimposed relation to one another therein, means for moving the films downwardly in the washing tank in superimposed relation to one another, means for removing the lowermost of the films successively from the washing tank, a drier to which the films are delivered, and means for moving the films with relation to the drying device and ejecting them therefrom in a finished state.

2. In an apparatus for washing films, a washing tank having water supplying slots at the sides thereof with relation to which slots the edges of the films travel in their delivery to the tank, means for supplying water to the tank on planes above and below that occupied by the films in the tank, means to which the films are delivered for moving the films downwardly in the tank in superimposed relation to one another, and means for removing the lowermost of the films successively from the tank.

3. In an apparatus for washing films, a washing tank having water supplying slots at the sides thereof with relation to which slots the edges of the films travel in their delivery to the tank, means for supplying water to the tank on planes above and below that occupied by the films in the tank, means to which the films are delivered for moving the films downwardly in the tank in superimposed relation to one another, means for removing the lowermost of the films successively from the tank, a film drier, and a film conveyer between the said film removing means and the drier, whereby films issuing from the tank are delivered to the drier.

4. In a device for treating photographic films, a receptacle adapted to contain fluid for treating films, a receptacle in proximity thereto for containing fluid in treating films, means for moving superimposed films downwardly in the first mentioned receptacle, means for successively removing the lowermost of said films, means for delivering said films to the second mentioned receptacle in superimposed relation to one another, means for moving the films progressively downwardly in the second mentioned receptacle, means for successively removing the lowermost film from the second mentioned receptacle, and means for operating the aforesaid instrumentalities intermittently or proportionally.

5. In a device for treating photographic

- for treating films, a receptacle in proximity thereto for containing fluid in treating films, means for moving approximately horizontally superimposed films downwardly in the first 5 mentioned receptacle, means for successively removing the lowermost of said films, means for delivering said films to the second mentioned receptacle in superimposed relation to one another, means for moving the films 10 progressively downwardly in the second mentioned receptacle, means for successively removing the lowermost film from the second mentioned receptacle, means for operating the aforesaid instrumentalities intermittently 15 or proportionally, a drying mechanism to which the films are delivered from the second mentioned receptacle, and means for operating the aforesaid instrumentalities proportionally and in time.
- 20 6. In an apparatus for treating photographic films and washing the same, consisting of a receptacle, means for delivering film longitudinally of the receptacle, the said receptacle having conduits for water at the 25 sides of the receptacle and provided with approximately vertically disposed slots constituting water delivery ports adapted to deliver water against the edges of and between superimposed films, the said slots being 30 associated with means for directing water into the said receptacle in the direction of the movement of the films as they are delivered to the receptacle.
- 35 7. In an apparatus for treating photographic films and washing the same, consisting of a receptacle, means for delivering film longitudinally of the receptacle, the said receptacle having conduits for water at the sides 40 of the receptacle and provided with approximately vertically disposed slots constituting water delivery ports adapted to deliver water against the edges of and between superimposed films, and means for delivering water to the receptacle into engagement with the films 45 and exerting force on the films in the direction of the movement of the films in said receptacle.
- 50 8. In an apparatus for treating photographic films and washing the same, consisting of a receptacle, the said receptacle having conduits for water at the sides of the receptacle and provided with approximately vertically disposed slots constituting water delivery ports adapted to deliver water against 55 the edges of and between superimposed films, and means for delivering water to the receptacle in a downward and longitudinal direction with respect to the said receptacle.
- 60 9. In an apparatus for treating photographic films, a receptacle adapted to contain fluid and receive photographic films, means for delivering films to the receptacle and moving them longitudinally thereof, and means for delivering water to the receptacle at its 65 sides and exerting a force on the films to aid in moving them longitudinally of the receptacle, and maintaining the edges of the films out of contact with the sides of the receptacle.
10. In an apparatus for treating photographic films, a receptacle adapted to contain fluid and receive photographic films, means for delivering films to the receptacle and moving them longitudinally thereof, means for delivering water to the receptacle and exerting a force on the films to aid in moving them longitudinally of the receptacle, the said receptacle having water discharging slots at the sides for directing water transversely and longitudinally of the receptacle in engagement with films occupying the receptacle. 70 75 80
11. In an apparatus for treating photographic films, a receptacle adapted to contain fluid and receive photographic films, means for delivering films to the receptacle and moving them longitudinally thereof, means for delivering water to the receptacle and exerting a force on the films to aid in moving them longitudinally of the receptacle, the said receptacle having water discharging slots at the sides for directing water transversely and longitudinally of the receptacle in engagement with films occupying the receptacle, and a film transfer in the receptacle to which the aforesaid films moving means delivers films entering the said receptacle. 85 90 95
12. In an apparatus for treating photographic films, a film washing tank having vertically extending water delivery slots discharging into the sides of the tank, the walls of said slots being diagonal with respect to the sides of the tank, whereby water is directed transversely and longitudinally of the tank. 100
13. In an apparatus for treating photographic films, a receptacle adapted to contain fluid, a submerging worm rotatably mounted therein, a wheel rotatably mounted under the said worm and out of contact therewith, means for elevating the worm with respect to the wheel as the worm rotates for creating a clearance for the deposit of a film between the worm and the wheel, and means for communicating motion to the said worm. 105 110 115
14. In an apparatus for treating photographic films, a receptacle adapted to contain fluid, a film transfer therein including a worm having an approximately vertically disposed axis, means for moving the worm axially and holding it retracted, a feed wheel rotatably mounted below the worm and adapted to contact with the worm in ejecting films from the receptacle, the said worm having a recess in its end constituting a clearance for the periphery of the said wheel, and means for driving the aforesaid parts. 120 125
15. In an apparatus for treating photographic films, a receptacle adapted to contain fluid, a film transfer therein including a worm having an approximately vertically disposed axis, means for moving the worm axially and holding it retracted, a feed wheel 130

rotatably mounted below the worm and adapted to coact with the worm in ejecting films from the receptacle, the said worm having a recess in its end constituting a clearance
 5 for the periphery of the said wheel, means for driving the aforesaid parts, a drier in proximity to said receptacle, a conveyer extending from the said receptacle into operative relation with the drier, whereby films
 10 ejected from the receptacle are delivered to the drier, and means for operating the conveyer and the drier in synchronism.

16. In an apparatus for treating photographic films, a coil-form film holder adapted
 15 to receive films from an exposing chamber of said apparatus, a receptacle for developer in which the film holder is located, a fixing fluid receptacle in proximity thereto to which films are delivered from the film holder, and
 20 initially coated with fixing fluid in their travel to the fixing fluid receptacle, a film submerger and transfer adapted to receive films flatwise in superimposed relation to one another, means for moving the films downwardly, means for removing the films successively from the bottom of said superimposed films, a washing tank to which films are delivered from the fixing fluid receptacle, including a conveyer adapted to engage
 25 the films and force them into the washing tank, fluid pressure means for maintaining the films suspended and in motion in the said tank, a film submerger and transfer in said tank to which films in approximately
 30 horizontal superimposed relation are delivered, means for moving the films downwardly in the tank, means for removing the lowermost of the superimposed films from the tank progressively, a drier in operative relation to
 35 the said tank, including a conveyer for delivering films from the tank to the said conveyer, and means for operating the aforesaid mechanism synchronously.

17. In a conveyer for photographic films,
 45 a support for the films consisting of belt-like elements, rollers around which the said elements are looped, one of said rollers being on a plane higher than that of the other roller, the frame upon which the rollers are rotatably mounted being adapted to be located in a fluid receptacle, the relation of parts being such that the lowermost of the two rollers has its periphery above the level of fluid contained in the receptacle, whereby the conveyer element in its travel over the lowermost roller has its surface elevated above the fluid in the receptacle, and means for holding the film supporting surfaces of the conveyer element under the said fluid for a portion of its travel in the receptacle.

GEORGE C. BEIDLER.
